UNITED STATES PATENT OFFICE.

FRANCIS M. CRISWELL, OF WASHINGTON, DISTRICT OF COLUMBIA.

DESIGN FOR A PULSOMETER.

SPECIFICATION forming part of Design No. 22,198, dated February 7, 1893.

Application filed November 26, 1892. Serial No. 453,278. Term of patent 7 years.

To all whom it may concern:

Be it known that I, FRANCIS M. CRISWELL, a citizen of the United States, residing at Washington, in the District of Columbia, 5 have invented and produced a new and original Design for Pulsometers; and I do hereby declare the following to be a full, clear, and exact description of the same, reference being had to the accompanying drawing, forming 10 a part thereof

The invention consists in the shape or configuration of the pulsometer as shown in the accompanying drawing which is an elevation of the design.

15 The bulb *a* which is tapering at its lower extremity is connected to the tubular portion *b* by the neck *c*, and, where the said neck joins the tubular portion *b*, a tube *d* of a

smaller diameter than the neck *c* depends into the bulb *a*, which tube is continuous from 20 the bulb *a* to the tubular portion *b*. The tube has produced upon its surface the annular neck *f*, which neck is formed by the contiguous part or parts *e* being of a larger diameter than the said neck *f*. 25

Having thus described my design, I claim as new and desire to secure by Letters Patent:—

The design for a pulsometer, as herein shown and described. 30

In testimony whereof I affix my signature in presence of two witnesses.

FRANCIS M. CRISWELL.

Witnesses:

S. A. TERRY,

JAMES BRAGOINER.
